ATTORNEY

UNITED STATES PATENT OFFICE.

JOHN THOMAS McCUNE, OF DECATUR, MISSISSIPPI.

SASH FASTENER.

Application filed October 3, 1922. Serial No. 592,059.

To all whom it may concern:

Be it known that I, JOHN T. McCUNE, a citizen of the United States, residing at Decatur, in the county of Newton and State of Mississippi, have invented a new and useful Sash Fastener, of which the following is a specification.

This invention relates to sliding sash windows, such as are used on railroad coaches, street cars and the like, and has for its object the provision of a novel sash fastening means, including spring-pressed dogs carried by the sash and cooperating with a double series of notches in the sides of the window frame, whereby the sash may be held securely at any desired position, the dogs being retractable by movement of a thumb piece toward the sash handle or lift to permit the sash to slide freely.

The special object of the invention is to arrange the thumb piece above the sash lift so that it may be operated by the thumb of the operator to release the dogs from their engagement, the forefinger engaging the sash lift, the latter sustaining the entire weight and strain of lifting the sash after the dogs have been released.

To the attainment of the above objects and advantages, the invention consists in the details of construction and arrangement of parts to be hereinafter more fully described and claimed, and illustrated in the accompanying drawings, in which:

Figure 1 is a front elevation of a window equipped with my device, a portion of the frame being in section;

Figure 2 is a vertical section on the line 2—2 of Figure 1;

Figure 3 is a vertical section on the line 3—3 of Figure 2, and

Figure 4 is a detail section on the line 4—4 of Figure 3.

Referring more particularly to the drawings, the letter A designates a sash slidable within the window frame B, which has the rear side of its face formed with a series of ratchet like notches C, and recesses D. Mounted on the lower rail of the sash is the usual lift or handle E.

In carrying out my invention, I provide the opposite edges of the sash with casings 10, which are mortised therein as shown, and within each of which is pivoted at its upper end at 11, a depending dog 12, having an angular end 13, normally held in outwardly projecting position by a leaf spring 14,

which engages against the rear edge of the dog and the opposed wall of the casing 10. The casings are of course provided with openings through which the dogs project.

Journaled lengthwise of the bottom sash rail are two shafts 15, which have their inner ends formed with slots 16, and which have their outer ends extending into the casings 10, and terminating in flattened angular extensions or arms 17, which engage against the forward edges of the dogs. Recessed into the bottom sash rail is a housing 18, through the ends of which the shafts 15 extend, and this housing is located above the lift E. Bearings 15^a are provided for the ends of the shaft.

The operating means consists of a thumb lever 19, formed of a plate 20, which is bent intermediate its ends to define a sleeve 21, encircling the inner ends of the shafts 15, and further including a plate 22 which extends across this sleeve and which engages within the slots 16 of the shafts 15. The plate 22 lies beneath the plate 20 and they are secured together by means of a rivet 23.

Assuming that the device has been constructed and installed as above described, it will be seen that by grasping the lift E with the forefinger and pressing on the thumb lever 19 with the thumb at the same time, the shaft 15 will be rocked owing to the engagement of the plate member 22 through the slots 16, and this rocking movement of the shafts 15 will cause the arms 17 at the ends thereof to swing the dogs 12 rearwardly so as to withdraw the angular ends 13 thereof into the casings 10. The sash will be easily raised and lowered by pulling on the sash lift E as it is freely slidable within the frame when the dogs are thus retracted. When pressure upon the thumb lever 19 is relieved, the springs 14 operate to project the dogs so that they will engage within the notches C or recesses D, as the case may be. After the dogs have been retracted out of the recesses D, the sash may be raised as much as desired without it being necessary to press the thumb lever owing to the ratchet like formation of the notches C, but it is essential that the dogs be retracted before the sash can be returned to its lowered position. Owing to that fact, that the recesses D have their upper walls square instead of inclined, it is to be noted that the sash cannot be raised at all until the dogs are withdrawn from these recesses.

Hence the latch is locked when the dogs are in engagement with the recesses.

From the foregoing description and a study of the drawings it will be apparent that I have provided a simply constructed and consequently inexpensive and easily installed device for holding or securing a slidable sash either in closed position or in a partially open position. As the parts are so few it is apparent that there is practically nothing to get out of order, so that the device should have a long life and satisfactorily perform all of its functions.

Having thus described my invention I claim:

The combination with a window sash having a lift secured rigidly thereto, and a window frame provided with a plurality of ratchet-like notches and recesses, of sash holding means consisting of a pair of cas-

ings mounted in the sash, spring-pressed dogs pivoted within said casings and adapted to selectively engage said notches or said recesses, a pair of rock shafts having their outer ends formed with angular arms engaging said dogs, and a thumb lever secured rigidly to and connecting both of said shafts at their meeting inner ends, said thumb lever projecting out from the sash over the said lift, so that the thumb may press upon said lever to release the dogs, whereupon the sash may be raised by the forefinger engaging the lift, whereby all the strain and weight of raising the sash is borne by the sash lift.

In testimony, that I claim the foregoing as my own, I have hereto affixed my signature.

JOHN THOMAS McCUNE.
